COMBINATION FLEXIBLE DISPENSING CLOSURE CAP AND SUPPORTING LOOP

Morton B. Stull, Garfield, N. J.

Application April 1, 1957, Serial No. 45,526

Term of patent 14 years

(Cl. D58—26)

Fig. 1

Fig. 2 is a top plan view thereof; and

Fig. 3 is a front elevational view thereof.

The side not shown is the same as the side shown.

I claim:

The ornamental design for a combination flexible dispensing closure cap and supporting loop, as shown and described.
